E. M. BALLANTINE

SHUTTLE SPINDLE SPRING

Filed Sept. 16, 1924

Inventor:

E. M. BALLANTINE,

By Monroe E. Miller

Attorney.

UNITED STATES PATENT OFFICE.

EDEN MILTON BALLANTINE, OF PHILADELPHIA, PENNSYLVANIA.

SHUTTLE-SPINDLE SPRING.

Application filed September 16, 1924. Serial No. 738,102.

To all whom it may concern:

Be it known that I, EDEN M. BALLANTINE, a citizen of United States, residing at Philadelphia, in the county of Philadelphia and 5 State of Pennsylvania, have invented certain new and useful Improvements in Shuttle-Spindle Springs, of which the following is a specification, reference being had therein to the accompanying drawing.

10 The present invention relates to loom shuttles having bobbin spindles mounted therein to be swung out of and into the shuttles for the replacement of the bobbins thereon, and it is the object of the invention to provide 15 novel and improved spring means for effectively retaining the spindle in position within the shuttle.

With the foregoing and other objects in view, which will be apparent as the description 20 proceeds, the invention resides in the construction and arrangement of parts as hereinafter described and claimed, it being understood that changes can be made within the scope of what is claimed, without departing 25 from the spirit of the invention.

The invention is illustrated in the accompanying drawing, wherein—

Figure 1 is a view, partly in elevation and partly in section, showing the improved 30 spring means as embodied in a shuttle of conventional design.

Fig. 2 is a fragmentary plan view showing the springs.

The shuttle 7, which may be of any well 35 known construction, has an opening in which the bobbin spindle 8 is normally disposed longitudinally or axially of the shuttle, and said spindle has a shank 9 inserted through the spindle socket 10 which is pivotally 40 mounted on a transverse pivot pin 11 extending through the shuttle, so as to permit the spindle to be swung out of and back into the opening of the shuttle with the socket 10. The shank 9 has the opposite notches 45 12 at opposite sides of the pivot pin 11 to engage transverse stop pins 13 engaging through the shuttle, whereby to limit the movement of the spindle in one direction when swung into normal position within 50 the shuttle, one pin 13 being beyond the rear end of the socket 10, and said socket having the recess or opening 14 to accommodate the other pin 13.

Ordinarily, a leaf spring 15 is provided 55 for holding the spindle 8 and socket 10 in

position within the shuttle, said leaf spring 15 being secured to the shuttle 7 by a securing screw 16 or other securing element within a seat 17, and the free terminal of the spring bears against a contact portion or lug 18 of the socket 10 so as to exert pressure against the socket to swing the socket and the spindle and hold the spindle against the pins 13. Such spring has been a source of annoyance because the spring may weaken 60 and permit the spindle to vibrate or swing out of normal position. The parts described up to this point are common and well known in shuttles, and in order to increase the power and efficiency of the spring means, an 65 additional or supplementary spring is used 70 as will presently appear.

A leaf spring 19 is secured against the leaf spring 15 within the seat 17 by the screw or securing element 16, and is longer 75 than the spring 15 so as to extend beyond the free end of said spring 15. The free terminal of the spring 19 is bent back inwardly, as at 20, in hook formation so as to bear against the contact point or lug 18 of the 80 spindle socket, with the spring 15 located within the hook portion of the spring 19 and bearing against the terminal portion 20. Thus, both springs exert pressure against 85 the spindle socket to hold the spindle in proper position within the shuttle, and by disposing the bent back terminal 20 of the spring 19 between the spindle socket and spring 15, the strength and holding power 90 of the spring means is increased considerably and is more efficient.

The spindle can be swung out of the shuttle and removed conveniently. Thus, by swinging the spindle (upwardly as seen in Fig. 1) the spindle is swung away from the 95 pins 13, and the contact point or lug 18 will, by cam action, bend the springs 15 and 19 outwardly, the spindle 8 being readily withdrawn from the socket 10 as soon as the spindle is swung out of the shuttle away 100 from the pins 13.

The supplementary or additional spring 19 can be readily applied to shuttles already in use, by using the same securing screw or element 16 which fastens the spring 15 to 105 the shuttle, and inserting the end portion or terminal 20 between the spring 15 and spindle socket. As shown, the springs 15 and 19 have the enlarged portions 21 surrounding the apertures through which the 110

2
screw 16 extends, and said springs have the tail portions 22 extending beyond the portions 21.

Having thus described the invention, what is claimed as new is:—

1. The combination with a shuttle and a spindle socket pivotally mounted therein, of a pair of leaf springs secured at substantially the same point to said shuttle and extending therefrom in substantially the same direction, one spring being longer than the other and having a bent back terminal disposed between the second named leaf spring and socket with the second named leaf spring overlapping and bearing against said terminal.
2. The combination with a shuttle and a spindle socket pivotally mounted therein, of a leaf spring secured to the shuttle with its free end in overlapping relation with said socket, and a longer leaf spring also secured to the shuttle at that side of the

first named leaf spring opposite to said socket and projecting in the same direction as the first named leaf spring, the second named leaf spring having its free terminal bent back around the free end of the first named leaf spring and disposed between and contacting with said socket and first named leaf spring.

3. Spring means for the pivoted spindle socket of a shuttle including a pair of leaf springs having corresponding portions to be secured at the same point of attachment to the shuttle with the springs extending in the same direction, one spring being longer than the other and having its free terminal bent back around the end of the other spring to be disposed between said other spring and the socket.

In testimony whereof I hereunto affix my signature.

EDEN MILTON BALLANTINE.
